H. S. Bailey, Attorney.

UNITED STATES PATENT OFFICE.

WILLIAM M. RHOADS, OF DENVER, COLORADO.

DESIGN FOR A BOOK-COVER.

No. 37,511.

Specification for Design.

Patented Aug. 15, 1905.

Application filed June 12, 1905. Serial No. 264,961. Term of patent 14 years.

To all whom it may concern:

Be it known that I, WILLIAM M. RHOADS, a citizen of the United States of America, residing in the city and county of Denver and State of Colorado, have invented a new, original, and ornamental Design for a Book-Cover, of which the following is a specification, reference being had to the accompanying drawing, forming part thereof.

The figure is a plan view of a book-cover, showing my new design.

I claim—

The ornamental design for a book-cover, as shown.

WILLIAM M. RHOADS.
